UNITED STATES PATENT OFFICE.

HARRY McNAIR AND JAMES G. GREENWOOD, OF FORT MADISON, IOWA.

ENVELOPE FOR KEEPING RECORDS.

Application filed February 4, 1926. Serial No. 86,050.

The object of our invention is to provide a novel type of envelope for use by merchants or others desiring to keep a record of the contents placed in the envelopes; to provide an envelope so constructed as to permit free use of carbon paper; and to provide a novel arrangement of the flaps, etc. We attain these and other objects of our invention by the envelope illustrated in the accompanying drawings, in which—

Figure 1 is a perspective view of the envelope with the carbon paper inserted for use;

Fig. 2 is a section on line 2—2 of Fig. 1;
Fig. 3 is a section on line 3—3 of Fig. 1; and

Fig. 4 is an illustration of the blank from which the envelope is made.

Like characters of reference designate like parts in each of the several views.

Referring to the accompanying drawings, I provide a blank portion 1 which constitutes the back of the envelope and which is left without any printing in order that the address may be written thereon if desired. 3 indicates the strip of the envelope which forms the front thereof and which bears the headings and blank lines shown for insertion of data concerning contents of the envelope.

We provide narrow side strips 10 and 11 on either side of the back 1, these wide strips each having longitudinal portions of the strips gummed, as indicated by the characters 13 and 14. Strip 10 is folded along the line 8 and strip 11 is folded along the line 9. The front strip 3 is then pasted on the narrow strips 10 and 11, as shown in Fig. 2. We provide a short sealing flap 5 extended over back 1, as shown in Fig. 3 and adapted to fold over the open end of the envelope, as shown in Fig. 1. Its inner portion has the gummed portion 12 by which it may be sealed to the end portion of front strip 3. We provide the extended flap 7 integral with flap 5 but having a line of perforations 6 separating them to permit of conveniently tearing strip 7 from the gummed flap 5. Strip 7 bears indicia markings and blank lines on its outer surface corresponding in position and arrangement with the indicia markings and blank lines on the front strip 3 of the envelopes. In use, the desired contents are placed in the

envelope, a sheet of carbon paper 1 is inserted between strips 7 and face 3 of the envelopes and data is entered in regard to the contents of the envelope on the printed form, a duplicate record thus being made. The strip 7 is then torn off along perforation 6, leaving the short gummed flap 5 to be used in sealing the envelope. The long strip 7 which is torn off is returned to the office file while the articles of record are transmitted in the sealed envelope with a record of its contents recorded by the sheet of carbon on its face 3. The back 1 of the envelope may be either left blank or an address filled in as the user may desire. It will be noted that the strip 7 extends the full length of the envelope. It will also be noted that the gumming of the narrow strips 10 and 11 to the edges of said face strip, leaves a clear smooth space over the main body of the strip for permitting of entering data in the printed form without the pen or pencil coming in contact with overlapping portions of the envelope flaps.

What we claim is:

1. The combination of an envelope with detachable flaps extending substantially the full length of the envelope, comprising a strip forming the back, narrow longitudinal gummed strips on either side thereof, a longitudinally aligned strip bearing indicia markings and blank lines and folded over the back strip and fastened to the gummed strips to form an envelope, and an opposite longitudinally aligned strip bearing identical indicia markings and blank lines positioned to overlie the first mentioned aligned strip to permit of recording matter in duplicate on the last mentioned strip and on the envelope body, a row of perforations in said last mentioned strip to permit of tearing same off, and a short gummed flap adjacent said row of perforations to permit of sealing the envelope and its contents and also recording the data regarding the transaction on the body of the envelope.

2. The combination in an envelope for record purposes, of a strip forming the back, narrow gummed opposite longitudinal strips, an end extension strip aligned longitudinally with the back strip and adapted to be glued to the gummed strips to form an envelope, said strip bearing indicia markings on its outer portion, an opposite end

extension flap aligned longitudinally with the back strip and extending substantially the full length of the envelope, said flap bearing indicia markings corresponding with those on the body of the envelope to permit making of duplicate records, and a row of perforations across said flap in prox-

imity to the end of the envelope to permit of detaching the flap for use as a duplicate record of transactions with reference to the 10 contents of the envelope.

HARRY McNAIR.
JAMES G. GREENWOOD.
